(57) **CLAIM**

I claim the ornamental design for a combined cap and dispensing nozzle, substantially as shown and described.

DESCRIPTION

FIG. 1 is a perspective view of a combined cap and dispensing nozzle in accordance with the present design shown with the cap removed for clarity of disclosure;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a bottom plan view thereof;

FIG. 7 is a top plan view thereof;

FIG. 8 is an exploded perspective view of a combination dispensing nozzle and cap for the nozzle in accordance with the present design; and,

FIG. 9 is a perspective view of the combined cap and dispensing nozzle shown in FIG. 1 in an environment of use. The features shown in broken lines in the various figures form no part of the claimed design.
